UNITED STATES PATENT OFFICE.

WILLIAM C. DEVEREAUX, OF DETROIT, MICHIGAN.

LATCHING MEANS FOR DOOR-LOCK HANDLES

Application filed May 4, 1927. Serial No. 188,720.

This invention relates to means for securing the handle shafts of locks for vehicle doors and the like, and has for one of its objects the provision of means for removably securing the handle shaft to interior portions of the lock whereby the shaft is readily rotatable, but is held against longitudinal movement while the lock is in locked position.

Another object of my invention is the arrangement of a handle shaft having a circumferential groove and a polygonal rear portion adjacent the actuating cam of the lock when the shaft is assembled, the polygonal portion being adapted to enter a similarly shaped aperture in the hub of the actuating cam, and the grooved portion serving in conjunction with a lock plate to prevent unwarranted withdrawal of the handle shaft from its assembled position.

A further object of my invention is the arrangement with a handle shaft having a polygonal extremity and a circumferential groove of a fixed locking plate having a polygonal aperture therein in horizontal alignment with a similarly shaped polygonal aperture in the hub of the actuating cam of the lock mechanism, all of the walls of the two polygonal apertures being in substantial alignment when the cam and shaft are turned to retract the locked bolt toward its unlocked position, and the walls of the two apertures being angularly disposed relatively to each other when the cam and lock bolt are in locked position.

Other objects and advantages will be apparent from the following description, wherein reference is made to the accompanying drawings, illustrating a preferred embodiment of my invention.

In the drawings:

Fig. 1 is a rear elevation of a lock for vehicle doors adapted for use with my improved handle shaft securing means.

Fig. 2 is an enlarged horizontal section showing the handle shaft and lock in positions assumed when the lock bolt is in locked position, with one means of arranging the handle relatively to the door.

Fig. 3 is an enlarged detail elevation showing the relative positions of the polygonal apertures in the lock plate and actuating cam respectively when the lock is in locked position.

Figs. 4 and 5 are detail perspective views

showing the rear portion of the lock shaft and the actuating cam respectively.

Fig. 6 is a rear elevation of a door lock having a remote control means for sliding the lock bolt.

Fig. 7 is an enlarged horizontal section showing the locked position of the lock bolt shown in Fig. 6 and with another means of arranging the handle relatively to the door, taken substantially on the line 7—7 of Fig. 6.

Fig. 8 is a detail sectional view taken substantially on the line 8—8 of Fig. 6.

Fig. 9 is a side elevation of a key used for initially positioning the lock bolt to permit ready insertion of the handle shaft, and

Fig. 10 is an end view thereof.

Referring now to the drawings, the numeral 5 designates a portion of the vehicle door, and 6 a lock casing adapted to be secured to the door by screws 7 or the like. The lock casing 6 carries a slideable lock bolt 8 having a portion normally extended beyond the lock casing by means of the spring 9 or other suitable means. The extended portion of the lock bolt 8 is adapted to engage a striker plate (not shown) carried by the door jamb, and the extended portion may be withdrawn from engagement with the striker plate by means of the actuating cam 10, mounted in the lock casing and having an offset portion 10a adapted to engage an offset arm 11 of the lock bolt 8 (note Fig. 1). The actuating cam 10 is adapted to be rotated by a handle shaft 12, carried by the door handle 13, which is usually arranged on the outer side of the vehicle door. In addition a vertical spindle 14 may be arranged with its handle 15 adjacent the inner side of the vehicle door to enable the ready unlocking of the door by persons within the vehicle. As shown in Fig. 1, the spindle 14 is provided with a crank portion 14a adapted to contact a shoulder 8a on the lock bolt, a light coil spring 16 being arranged to normally urge the crank portion of the spindle away from the shoulder 8a.

The parts above described may vary in many particulars, and are intended to show one embodiment of a vehicle door and lock with which my improved handle shaft and securing means are useful. The illustrations of the above described parts are merely for

purposes of exemplification, and it is to be understood that the claimed invention herein disclosed is adaptable for use with other forms of locks, etc.

- 5 My improved handle shaft 12 is formed with a polygonal rear portion 12^a separated from the main portion of the shaft by a circumferential grooved portion 12^b, as shown in Figure 4. In the illustrated em-
10 bodiment the rear portion 12^a of the handle shaft is squared, and is adapted to fit within the polygonal aperture 10^b in the hub of the actuating cam 10, substantially as shown in Figures 2 and 7, the grooved portion 12^b of
15 the lock shaft being then arranged adjacent the forward face of the actuating cam 10 and within a polygonal aperture 17^a in the shaft locking plate 17, fixed within the lock casing, as by welding upon the inner plate of the
20 lock casing, as shown in Figs. 1-3, or by suitably shaping such inner plate itself, as shown in Figs. 6 and 7. As herein shown the walls of the polygonal aperture 17^a are disposed at substantially right angles to the walls of
25 the aperture 10^b in the actuating cam (note Fig. 3), and as long as these apertures maintain such relative position the walls of the circumferential groove 12^b will contact the shaft locking plate 17, if the handle shaft be
30 moved longitudinally in either direction. When, however, the handle shaft is turned to bring the walls of the polygonal aperture 10^b into alignment with the walls of the aperture 17^a in the locking plate, the walls
35 of the groove 12^b will no longer contact the shaft locking plate 17 to prevent longitudinal movement of the shaft. In other words, as long as the aperture 10^b of the cam is obliquely disposed relatively to the aperture 17^a in the locking plate 17 the corners of the
40 lock shaft are similarly obliquely disposed to the aperture in the locking plate, and withdrawal of the lock shaft is prevented because the corners of the shaft forming the side walls of the groove 12^b would engage the locking plate 17 whenever attempt is made to move the shaft longitudinally.
45 This provides a very simple and effective means for preventing unwarranted withdrawal of the handle shaft, the shaft being held against longitudinal movement beyond the width of the groove 12^b until the shaft is turned to accurately align the walls of the polygonal apertures 10^b and 17^a respectively. When the apertures are so aligned, however, the handle shaft can be readily withdrawn. If desired, the width of the circumferential groove 12^b may be but slightly greater than the width of the locking plate 17, in which case the permitted longitudinal movement or "play" of the handle shaft in locked position would be practically nil. However, for enabling ready assembly of any of a number of handle shafts into
50 any of a group of lock casings I preferably provide circumferential groove portions 12^b of sufficient width to allow for the usual differences in width of vehicle doors, imperfect positioning of lock casings upon the door, and other minor defects continually met with in building and assembling vehicle doors and the like. By forming the groove 12^b with a width equal to the difference between the maximum and minimum tolerances in the width of the vehicle doors, I can insure ready assembly of any handle shaft into any lock casing on an acceptable door, and the speed of assembly may be materially increased, while the labor cost of fitting locks and handle shafts into position is materially decreased.
- 55 In assembling my improved handle shaft into the lock casing, the actuating cam 10 is swung to bring its aperture 10^b into complete alignment with the aperture 17^a in the locking plate, whereupon the handle shaft may be readily inserted through the passage-way 18 in the door 5, the aperture 17^a in the lock plate 17 and into the aperture 10^b of the actuating cam. The actuating cam 90 may then be released and the spring 9 forces it to its normal position with the lock bolt 8 extended, this return swinging movement serving to turn the handle shaft 12 to a position obliquely disposed relatively to the aperture 17^a in the lock plate 17. To readily accomplish the initial swinging of the actuating cam to permit the insertion of the lock shaft, I preferably provide a key 19 having an octagonal rear portion (note Figs. 9 and 10) insertable through both the aperture 17^a in the locking plate and 10^b in the cam. By suitably turning the key after such insertion the aperture 10^b in the cam 100 may be swung into complete alignment with the aperture 17^a in the locking plate, whereupon the cam is manually held in such position while the key 19 is withdrawn and the handle shaft 12 inserted. During such swinging movement of the cam by the key 19 the lock bolt 8 is retracted, either partially or completely as desired by the lock manufacturer, against the tension of the spring 9. Then after the shaft has been inserted into the aperture of the cam, the pressure on the tool is released, permitting the spring 9 to return the lock bolt 8 and cam to their original positions. One means for maintaining the cam in the desired position with its aperture 10^b aligned with the aperture 17^a of the locking plate 17 is shown in Figs. 6-8. A remote control lever 26 pivoted upon a plate 27 fixed within the automobile door at a distance from the lock casing 6 is connected by an elongated link 28 with a slid able plate 29 guided for movement on the lock casing and carrying a lug 30 engaging the rear portion 8^a of the lock bolt 8.
110 Means may also be provided adjacent the 130

forward extremity of the lock shaft for giving a uniform appearance to the handle and adjacent portion of the lock shaft regardless of the differences in the width of the vehicle door. In Figure 2 I have illustrated a spacer tube 20 surrounding the lock shaft adjacent the handles and extending within an escutcheon plate 21. Both the spacer tube and escutcheon plate may be of various ornamental shapes and their surfaces nickelized or otherwise finished as desired. The escutcheon plate is preferably formed with ears 22 on its rear extremity adapted to be engaged by a washer 23, while another washer 24 surrounds the shaft 12 and engages the rear extremity of the spacer tube 20. A coil spring 25 is arranged between the washers 23 and 24 and serves to both hold the escutcheon plate in position upon the door and force the lock shaft 12 outwardly as far as permitted by the rear wall of the circumferential slot 12^b when in engagement with the lock plate 17. Regardless of the extent of overlapping of the spacer tube 20 and escutcheon plate 21 the appearance of the handle end of the lock shaft is substantially the same, and this overlapping arrangement in conjunction with the comparatively wide circumferential slot 12^b permits the use of lock shafts 12 of the same length on doors 5 of various widths. Or an escutcheon plate 31 may be directly secured upon the door 5 by screws 32, as shown in Fig. 7, passing through apertures in the metal cover plate of the door. In this embodiment the escutcheon 31 may be stiffened by a suitable backing plate 33 having lugs 34 also adapted to pass through apertures in the metal door covering, while a light spring 35 may be arranged between the backing plate and a washer 36 surrounding the shaft and held against longitudinal movement thereon by struck up portions 37 of the handle shank.

While it will be apparent that the illustrated embodiment of my invention herein disclosed is well calculated to adequately fulfill the objects and advantages primarily stated, it is to be understood that the invention is susceptible to variation, modification and change within the spirit and scope of the annexed claims.

Now having described my invention I claim:

1. The combination with a lock casing having a lock bolt and actuating cam therefor provided with a polygonal aperture, of a fixed locking plate having a polygonal aperture therein and a rotatable handle shaft having a polygonal rear portion adapted to fit within the aperture in the cam and a circumferentially grooved portion adapted to normally extend through the aperture in the locking plate, the walls of the apertures in the cam and locking plate being angularly disposed relatively to each other while the cam and lock bolt are in their locked positions.

2. The combination with a lock casing having a lock bolt and actuating cam therefor provided with a polygonal aperture, of a fixed locking plate having a polygonal aperture therein and a rotatable handle shaft having a polygonal rear portion adapted to fit within the aperture in the cam and locking plate being angularly disposed relatively to each other while the cam and lock bolt are in their locked positions. 70

3. The combination with a lock casing having a lock bolt and actuating cam therefor provided with a polygonal aperture, of a handled lock shaft having a polygonal portion adapted to fit within the aperture in said cam and an annular groove adjacent said polygonal portion, and means for removably securing the shaft against unwarranted withdrawal from the cam including a fixed locking plate having a polygonal aperture surrounding said annular groove and arranged in horizontal alignment with, but with its walls angularly disposed relatively to, the normal positions of the walls of the aperture in said cam.

4. The combination with a lock casing having a lock bolt and actuating cam therefor provided with a polygonal aperture, of a handled lock shaft having a polygonal portion adapted to fit within the aperture in said cam and an annular groove arranged between the handle and said polygonal portion, and means for removably securing the shaft against unwarranted withdrawal from the cam including a locking plate fixed between the handle and the cam and having a polygonal aperture surrounding said annular groove and arranged in horizontal alignment with, but with its walls angularly disposed relatively to, the normal positions of the walls of the aperture in said cam.

5. The combination with a lock casing having a lock bolt and actuating cam therefor provided with a polygonal aperture, of a handled lock shaft having a polygonal portion adapted to fit within the aperture in said cam and an annular groove arranged between the handle and said polygonal portion, and means for removably securing the shaft against unwarranted withdrawal from the cam including a locking plate fixed between the handle and the cam and having

a polygonal aperture surrounding said annular groove and arranged in horizontal alignment with, but with its walls angularly disposed relatively to, the normal positions of the walls of the aperture in said cam, and means arranged between the handle and said fixed plate for pressing the handle of the lock shaft longitudinally

away from the locking plate to maintain one of the side walls of said groove in contact with the locking plate while said apertures are angularly disposed relatively to each other. 10

In witness whereof I hereunto set my hand.

WILLIAM C. DEVEREAUX.
